(57) **CLAIM**

The ornamental design for a mount for surveillance camera as shown and described.

DESCRIPTION

FIG. 1 is a front perspective view of a mount for surveillance camera showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a right side view thereof showing a state in which a surveillance camera and a wall mount are coupled by the mount for surveillance camera.

The broken lines in the drawings depict portions of the surveillance camera and the wall mount coupled by the mount for surveillance camera, and form no part of the claimed design.

1 Claim, 8 Drawing Sheets
